Des. 197,220
Patented Dec. 31, 1963

197,220

TELEPHONE BOOTH FOR GROUP USE

Henry Dreyfuss, South Pasadena, Calif., assignor to Bell
Telephone Laboratories, Incorporated, New York,
N.Y., a corporation of New York

Filed Nov. 13, 1962, Ser. No. 72,450

Term of patent 14 years

(Cl. D13—1)

FIG. 1

FIG. 2

FIG. 3

FIG. 1 is a perspective view of a telephone booth for group use showing my new design;

FIG. 2 is a side elevational view of the telephone booth for group use shown in FIG. 1; and

FIG. 3 is a top plan view of the telephone booth for group use shown in FIG. 1.

The dominant features of my new design reside in the portions shown in solid lines on the drawing.

I claim:

The ornamental design for a telephone booth for group use, as shown and described.
